UNITED STATES PATENT OFFICE.

FRANZ A. FULLER, OF NEWARK, NEW JERSEY, ASSIGNOR TO THE J. E. MEROOTT COMPANY, OF NEWARK, NEW JERSEY, A CORPORATION OF DELAWARE.

HINGE.

1,408,727.

Specification of Letters Patent.

Patented Mar. 7, 1922.

Application filed November 5, 1920. Serial No. 421,840.

To all whom it may concern:

Be it known that I, FRANZ A. FULLER, a citizen of the United States, residing in Newark, in the county of Essex and State 5 of New Jersey, have invented certain new and useful Improvements in Hinges, of which the following is a specification.

The main object of this invention is to provide a novel type of hinge, particularly 10 adapted for use in connecting the lids or cover to the bodies of a metal receptacle.

Other objects are:—to provide a hinge the side-elements of which are integral with the cover and body respectively, but so 15 arranged as to require no material other than that contained in the normal blanks for these parts; to avoid the use of rivets, solder or like fastening means; to provide a hinge that when assembled forms part of 20 the wall of the container, acting as a reinforcement and presenting no opening for the passage of air or matter; and finally, to provide a hinge of exceptional strength, inflexibility and neatness of appearance.

25 These objects are attained by the novel construction, combination and arrangement of parts, hereinafter described and shown in the accompanying drawings forming a material part of this disclosure, and in 30 which:—

Figure 1 is a perspective view of a conventional type of round metal box and lid united by a hinge made in accordance with the invention.

35 Figure 2 is a similar view of the lid in detail.

Figure 3 is a like view of the box body in detail.

Figure 4 is an enlarged plan view of the 40 box and lid shown in an open position.

Figure 5 is a perspective view of the hinge bearing or connecting element in detail.

Figure 6 is an enlarged fragmentary sectional view of the box, lid and hinge, the lid 45 being raised.

Figure 7 is a fragmentary view of the hinge and its attached parts, looking from the interior of the box.

Referring to the drawings in detail the 50 numeral 10 designates the body of a common type of small metallic container, the same having a bottom 11 and provided with a bead 12 at its lower edge, a similar bead 14 being formed annularly around its circum-

ference at a point below its open upper portion 15.

The lid or cover is comprised of a crown plate 16 beaded at its margin 17, the bead blending into an annular flange 18, adapted to engage over the circular upper portion 60 15 of the box and rest upon the beading 14.

The flange 18 contains a shallow curved recess 19, at a point adjacent the hinge to permit the lid to be freely operated, the ends 65 19' of the recess being sharply defined.

Midway between the ends of the recess 19 the material of the flange is slit and pressed outward, forming a pair of outstanding lugs 20 containing small round openings 21, the lugs having their edges curved in conformity 70 with the axis of the openings, which are in alignment, and an open space 22 presented between the lugs, as best shown in Figure 2.

The box body portion 15 has a similar cut-out 24 having outstanding curved lugs 75 25 containing aligned perforations 26, the lugs or ears 25 being spaced apart so as to neatly fit between the corresponding parts 20 of the lid.

The connecting element, as shown in detail in Fig. 5, is comprised of a single flat blank of sheet metal formed to present a tubular element 28 in length just sufficient to fill the space between the lugs 25 of the 80 box body.

Extending from the longitudinal joint of the tube are two plate connections 29 tightly pressed together these elements being coincident in length with the tube and terminating in oppositely disposed flanges 30, 90 curved to agree with the inner diameter of the box body and increased in length to extend over the opening 24 and slightly past the lugs 25, when assembled on the box body, the arrangement being best seen in 95 Figs. 6 and 7.

When so assembled a hinge pin 31 is passed through the perforations in the lugs of both lid and body and also through the tube 28 forming a neat, strong and effective 100 hinge, the axis of which is so positioned as to permit the lid to be reversed upon the pin, allowing full access to the box, and when the lid is closed, presents no openings for the passage of matter.

105 In the case of a rectangular box it is apparent that two or more of the hinges may be applied as may be required,

If the hinge be properly proportioned to the receptacle it will be found exceptionally stiff to resist lateral pressure, causing the lid to correctly center with the body of the box.

Another feature is that the lid is held resiliently when in a closed position, due to the engagement of the outer ends 19' of the recess 19, on the upper part 15 of the box, 10 the tension of the flange being exerted when the lid is raised and which suffices to maintain the lid in engagement when snapped shut during ordinary handling, including reversing the normal position of the box.

15 It is also noticeable that the upper element of the flanges 30 extends above the edge of the box so as to completely cover the opening 22 between the lugs 20 when the lid is closed.

In applying the hinge it is to be noted 20 that the lugs 25 are held in compression between the ends of the hinge pin and overlying ends of the flanges 30, the elements 29 being in tension so as to hold the connecting element firmly in position and without affecting freedom of lid movement, no extraneous securing means being required.

The disclosure is to be regarded as descriptive only, and not as restrictive or limitative of the invention, of which obviously 30 an embodiment may be constructed including many minor modifications without departing from the general scope herein in-

dicated and denoted in the appended claims:

1. A hinge for connecting a lid to a container, comprising spaced paired lugs extending respectively from the lid and container, one pair being embraced within the other, there being open spaces between the lugs, a tube disposed between the inner pair of lugs, projections formed with said tube extending through the open space in the container and flanges at the inner ends of said projections adapted to engage the interior of the container, the ends of said flanges extending past the bases of said lugs 45 thus covering the mentioned open spaces.

2. In combination with paired lugs extending respectively from a box and its lid, leaving spaces therebetween, of a hollow spacer between the inner pair of lugs, extension formed with said spacer passing through the space in said box, flanges formed with said extensions disposed over the space and within the box, the upper portion of said flanges covering the space in 55 said lid when closed and a pivot pin passing through said lugs and said spacer.

This specification signed and witnessed this fourth day of November, 1920.

FRANZ A. FULLER.
